BOWLING ALLEY SANDING MACHINE

John W. Bryan, Traphill, N. C.

Application July 8, 1947, Serial No. 759,513

2 Claims. (Cl. 51—176)

1

This invention relates to floor sanding machines, and more particularly to a sanding machine for resurfacing bowling alley floors.

A main object of the invention is to provide a novel and improved bowling alley surfacing machine which is very simple in construction, easy to use and efficient in operation.

A further object of the invention is to provide an improved surfacing machine for bowling alleys which involves only a few easily assembled parts, which is reliable in performance and which is automatic in operation.

Further objects and advantages of the invention will become apparent from the following description and claims, and from the accompanying drawings, wherein:

Figure 1 is a top plan view of a bowling alley on which is positioned a surfacing machine constructed in accordance with the present invention.

Figure 2 is a transverse vertical cross-sectional view taken on line 2—2 of Figure 3.

Figure 3 is a side elevational view of the surfacing machine of Figure 1.

Figure 4 is an enlarged elevational detail view of an alternative front supporting member for the surfacing machine carriage of Figure 1.

Figure 5 is a cross-sectional view taken on line 5—5 of Figure 4.

Referring to the drawings, 11 designates a conventional bowling alley having a bowling floor surface 12 and the side channels 13, 13. The surfacing machine comprises a frame 14 extending substantially for the transverse width of floor surface 12 and in the rear portion of which is transversely journaled a sanding drum 15. The rear end of frame 14 is supported on a transverse roller 16 which is journaled in vertically adjustable bearing brackets 17, 17, depending from the frame, and the front end of the frame is supported on a longitudinally extending bracket member 18 secured to the front end of the frame by an upstanding central arm 19 carried by said bracket member. Journaled to the forward and rear ends of bracket member 18 are wheels 20 bearing on the bowling alley floor surface 12.

Mounted on the forward portion of frame 14 is an electric motor 21 having a transversely extending shaft 22. Secured to shaft 22 is a pulley 23 which is coupled by a belt 24 to a pulley 25 carried by the shaft of sanding drum 15. Mounted on the frame 14 adjacent the sanding drum is a suction pump 26 having an intake housing 27 extending transversely across the frame forward.

2

ly adjacent the sanding drum surface and having a dust bag 28 detachably secured to the outlet conduit thereof, said bag being supported by suitable detachable fastening means secured to an upstanding post member 29 carried by frame 14. The shaft of pump 26 carries a pulley 30 which is coupled by a belt 31 to a pulley 32 secured to motor shaft 22.

10 Journaled transversely in the forward end portion of frame 14 is a shaft 33 carrying a drum 34 on which is wound a cable 35. Cable 35 extends over a pulley 36 journaled in brackets 37 carried by a plate member 38 secured to the wall at the front of the alley. Cable 35 extends rearwardly 15 from pulley 36 over a pulley 39 journaled in the front end of frame 14 and thence forwardly to a hook 40 carried by plate member 38, to which hook said cable is secured. Shaft 33 carries a pulley 41 which is coupled by a belt 42 to a pulley 20 43 carried on motor shaft 22.

Secured to the sides of frame 14 at its rear portion are depending arms 44, 44 on which are journaled guide rollers 45, 45 engaging the inner side walls of the channels 13, 13 so as to guide 25 the frame 14 longitudinally with respect to the alley floor surface.

The cable 35 has adjustably secured thereto a stop member 46 which is adapted to engage the operating button of a switch 47 depending from 30 the forward end of frame 14 rearwardly adjacent pulley 39. Switch 47 is normally closed and is in series with motor 21. Said switch is adapted to be opened when its operating button is engaged by stop member 46 at the desired forward 35 limiting position of the frame 14, thereby automatically opening the motor circuit at this position of the frame. By positioning stop member 46 at different positions on cable 35 said forward limiting position may be varied.

40 In operation, motor 21 drives the sanding drum 15, the suction pump 26 and the cable winding drum 34 simultaneously, causing the frame 14 to be moved forwardly over the alley floor surface 12 while said floor surface is smoothed by sanding drum 15. The sand and wood dust is drawn into bag 28 by the suction pump 26. When stop member 46 engages the actuating button of switch 47 the machine stops and may be then reset to repeat the sanding operation on the same 45 alley or may be moved to another alley for smoothing the floor thereof.

Instead of employing the elongated front supporting bracket member 18, the front end portion of frame 14 may be supported on a single-wheeled bracket 48 having the floor engaging wheel 49,

as shown in Figures 4 and 5, said bracket 48 being adapted to be connected to the frame 14 in place of the arm 19.

By removing the depending arms 44, 44 carrying the guide rollers 45, 45 the machine may be employed for sanding other than bowling alley floor surfaces.

The rate of movement of the frame may be varied by employing different pulley arrangements for the cable 35.

While a specific embodiment of a floor surfacing machine has been disclosed in the foregoing description, it will be understood that various modifications within the spirit of the invention may occur to those skilled in the art. Therefore it is intended that no limitations be placed on the invention other than as defined by the scope of the appended claims.

What is claimed is:

1. A bowling alley sanding machine, comprising a single low horizontally disposed frame, a horizontal sanding drum rotatably mounted upon the frame near its rear end and extending transversely of the frame, an elongated transversely extending roller mounted upon the rear end of the frame and depending therefrom and arranged rearwardly of and near the sanding drum, means to adjust the roller vertically with respect to the frame and sanding drum, a low horizontal longitudinally extending wheeled bracket disposed beneath the forward end of the frame and having an upstanding arm pivotally connected with the frame so that the frame can tilt when the roller is adjusted vertically to bring the sanding drum into contact with the alley, a suction device mounted upon the frame adjacent to the forward side of the sanding drum to collect dust formed by the drum, a cable reel mounted upon the frame near its forward end, a cable wound upon the reel and adapted for attachment to a stationary object at one end of the alley for pulling the machine over the alley during the sanding operation, a single motor mounted upon the frame between the sanding drum and cable reel, driving connecting means between the single motor, suction device and cable reel, and depending guide rollers secured to the sides of the frame near its rear end to engage the side channels of the alley

4
for guiding the machine, the motor rotating the sanding drum in a direction opposite to the direction of travel of the machine.

2. A bowling alley sanding machine, comprising a unitary low horizontal frame, a horizontal sanding drum rotatably mounted upon the frame near its rear end and extending transversely of the frame, an elongated transversely extending roller secured to the rear end of the frame and disposed beneath the frame and rearwardly of and near the drum, means to adjust the roller vertically, a low horizontal elongated wheeled bracket disposed beneath the frame near its forward end and extending longitudinally of the frame from a point substantially at the longitudinal center of the frame to a point forwardly of the frame and pivotally connected with the frame to permit the frame to tilt when the roller is vertically adjusted to bring the drum into contact with the alley, a suction device mounted upon the frame adjacent to the forward side of the drum and including a single elongated dust intake conduit extending longitudinally of the drum for substantially its entire length, a cable reel mounted upon the frame near its forward end and having its axis arranged transversely of the frame, a single motor mounted upon the frame near its longitudinal center and arranged between the drum and reel, belts connecting the armature shaft of the motor with the drum, reel and suction device to operate the same, and a cable wound upon the reel and having a free end for attachment to a stationary object near one end of the alley, the cable being wound up on drum to advance the machine during the sanding operation, the motor driving the drum in a direction opposite to the direction of travel of the machine.

JOHN W. BRYAN.
